UNITED STATES PATENT OFFICE.

WILLIAM H. WELCH, OF SALEM, OHIO.

POWER DROP-HAMMER.

1,304,426.

Specification of Letters Patent. Patented May 20, 1919.

Application filed December 26, 1917. Serial No. 208,725.

To all whom it may concern:

Be it known that I, WILLIAM H. WELCH, a citizen of the United States, residing at Salem, in the county of Columbiana and 5 State of Ohio, have invented certain new and useful Improvements in Power Drop-Hammers, of which the following is a specification.

My invention relates to improvements in 10 power hammers, and more particularly to that class or type of power actuated hammers known as "drop hammers."

The primary object of the invention is to 15 provide a generally improved power driven hammer of this class which will be exceedingly simple in construction, cheap of manufacture, and efficient in use.

A further object is the provision of improved hammer actuating and controlling 20 mechanism for a power hammer of this class, of simple and efficient construction, particularly adapted to meet the varying demands of actual service, and which will be under full and complete control of the operator at all times during the operation of 25 the hammer.

A still further object is the provision of 30 an improved power head, together with improved clutch and clutch actuating and controlling mechanism, whereby in connection with suitable foot or treadle operated mechanism suitably connected therewith, the operator may readily impart any desired stroke or fall to the hammer head from the 35 minimum to the maximum.

In carrying out the invention the power 40 driven shaft is provided with a suitable clutch, together with a suitable hammer actuating winding drum and suitable foot controlled clutch engaging and releasing 45 mechanism, whereby the hammer actuating drum may be intermittently moved in one direction for elevating the hammer and released and allowed to travel in an opposite direction for dropping the hammer, means being also provided whereby such clutch engaging and disengaging members may be brought into action at variable points in the revolution of the hammer actuating 50 drum thereby enabling the operator to impart a variable stroke to the hammer head, and as contradistinguished from the ordi-

nary power driven drop hammers where it is necessary to predetermine the length of drop or stroke desired for the work in hand and thereafter adjusting the hammer actuating and controlling mechanism accordingly.

With the above mentioned and other ends in view, the invention consists in the novel 60 construction, arrangement, and combination of parts, hereinafter described, illustrated in one of its embodiments in the accompanying drawings, and particularly pointed out in the appended claims.

Referring to the drawings, forming a part of this specification, Figure 1, is a front view of a power hammer constructed in accordance with my invention, the parts being 70 in their hammer releasing position, and the hammer head being in its lowermost or released position.

Fig. 2, a side elevation of the same.

Fig. 3, an enlarged vertical central sectional view of the power head and clutch 75 and clutch actuating and controlling mechanism.

Fig. 4, a cross sectional view taken on line 4—4, of Fig. 3.

Fig. 5, a cross sectional view taken on line 80 5—5 of Fig. 3.

Fig. 6, a cross sectional view taken on line 6—6, of Fig. 3.

Fig. 7, an enlarged end elevation of the power head, certain parts being broken 85 away for the purpose of clearer illustration of the clutch disengaging slide and slide actuating mechanism.

Fig. 8, an end elevation of the clutch disengaging slide removed, illustrating in particular the clutch disengaging stepped head.

Fig. 9, a side elevation of the clutch disengaging slide and slide actuating mechanism, certain parts being broken away for the purpose of clearer illustration of the 95 parts.

Fig. 10, an enlarged vertical sectional view of the power head and clutch and clutch actuating mechanism taken on line 10—10, of Fig. 1, the clutch disengaging 100 head and slide being removed for the purpose of illustration.

Fig. 11, an enlarged rear elevation of the same and of the clutch disengaging slide

and slide head, certain parts of the latter being broken away for the purpose of illustration.

Fig. 12, an enlarged horizontal sectional view taken on line 12—12, of Fig. 1, and illustrating in particular the foot or treadle control mechanism for coöperating with the clutch actuating and controlling mechanism.

10 Fig. 13, a fragmentary perspective view of one of the pivoted portions of the foot or treadle control mechanism.

Similar numerals of reference designate like parts throughout all the figures of the 15 drawings.

The improved drop hammer comprises a suitable frame consisting, in the present instance, of a base 1, adapted to support a suitable anvil block 2. The frame further 20 includes a pair of suitable vertical guide members 3.

The power head, in the present instance, comprises a suitable frame consisting of a cross or base member 4, mounted upon and 25 supported by the vertical guide members 3, and provided with bearing members or pedestals 4^a, provided with suitable bearing blocks 4^b, for carrying the driving shaft 5. The shaft 5, is adapted to be driven by 30 means of a driving pulley 5^a, and is further provided with a fixed clutch 6, the latter being secured to the shaft 5, by means of a key member 6^a, as shown in Fig. 3, of the drawings. The movable clutch member and 35 actuating mechanism and the hammer actuating mechanism may be of any suitable and convenient form, and in the present instance, comprises a movable clutch member 7, arranged within and in coöperative relation to the fixed clutch member 6, and provided with a hammer actuating member 8, in the present instance, in the specific form of a winding drum adapted to carry and operate the hammer strap 9^a, connected to a 40 hammer head 9, the latter operating between the guide members 3, in the usual manner. The hammer actuating or drum member 8, terminates at one side in a brake head or drum 10, said head or drum 10, being adapted to be controlled in the usual 45 manner by means of a brake strap 10^a, secured at one end by means of a bracket and cross pin 10^b, secured to the base member 4, of the frame, and the free end being connected to a connecting link or rod 11, extending downwardly and being connected at its lower end to a cross member 12^a, of an oscillatory foot treadle consisting of side members 12, pivotally mounted on trunnion 50 members 1^a, of the base 1, said foot controlled or treadle mechanism being constructed and operated as hereinafter described.

As a means of bringing the movable clutch member 7, and its connected members 8 and

10, into and out of engagement with the fixed member 6, during the rotation of the shaft 5, the movable or rotatably mounted clutch member 7, is provided with the split ring members 13, normally drawn toward 70 their retracted or disengaging positions by means of connecting springs 14, (see Fig. 4) connected to the brackets 13^a, said ring members 13, being adapted to be adjusted to compensate for wear, or the like, by 75 means of a wedge member 15, interposed between adjacent ends of the split ring members and adapted to be adjusted, in the present instance, by means of an adjusting bolt 16, and as a means of simultaneously moving the ring members 13, into and out of clutched relation with the adjacent surrounding fixed clutch 6, a rock shaft 17, is provided, said shaft being connected to the adjacent split ends of the ring members 80 by means of suitable links 17^a, and being provided at its opposite end with a trip arm 17^b, the latter being arranged at the face side of the brake drum portion of the movable clutch and consisting in the 85 present instance, of the dual heads or arms 17^c, and 17^d, adapted to alternately engage with the movable clutch engaging and releasing trip members or projections hereinafter referred to.

95 As a means of automatically causing the fixed clutch member 6, to engage with the movable clutch 7, at or near the bottom of the working stroke of the hammer as the latter descends by the release of the movable clutch member 7, and also to vary such point of the clutch reengagement to compensate for different thicknesses of dies or work being operated upon, a variable trip member 18, is provided, said trip member 100 18, in the present instance, being circumferentially movable on the driving shaft 5, and being provided with a trip projection 18^a, against which the arm or head 17^c, of the rock shaft 17, is adapted to contact 105 thereby rocking the latter to expand the ring members 13, into contact with the fixed clutch 6, whereby the latter with the rotation of the driving shaft 5, will elevate the hammer head 9, for another working stroke, 110 and as a means of adjusting the trip member 18, to compensate for the variable conditions above referred to, and particularly of catching the hammer head 9, on its rebound during its working stroke, the arm 115 of the trip member 18, is connected to a rod or link 19, the latter, in the present instance, being connected to a crank 20, on a shaft 21, the shaft 21, being mounted in a bracket 22, at the rear of one of the guide 120 members 3, and the shaft 21, being provided with a second crank 23, communicating with a second link 24, operated by means of a lever 25, on the front of the 125 machine frame within ready reach of the 130

operator, and adapted to be adjusted in an obvious manner through the medium of the notched segment 26, and in an obvious and well understood manner.

5 As a means of giving a variable release to the clutch and a consequently variable stroke to the hammer head 9, in accordance with the varying demands of actual service, a second trip head or member is provided, said trip head, in the present instance, comprising a head 27, provided with a flanged or rim portion 27^a, armed with a plurality of graduated trip projections 27^b, arranged in stepped relation to each other 10 and adapted to be moved into the plane of movement of the arm 17^d, of the trip member 17^b, of the rock shaft 17, as the latter is being carried upwardly and about by the rotation of the clutched member 7, and the 15 hammer actuating drum 8, and release the latter in any desired elevation or length of stroke predetermined upon by the operator through the foot controlled actuating mechanism hereinafter described.

20 25 As a convenient means of supporting and moving the head 27, and its projections 27^b, toward and from the plane of rotation of the trip arm portion 17^c, of the trip arm 17^d, the head 27, is mounted on a longitudinally 30 movable slide 28, adapted, in the present instance, to operate in guide ways 4^c, of one of the bearing blocks, said slide being provided with racks 28^a, meshing with geared segments 29, (see Figs. 7 and 9) carried on a 35 rock shaft 30, the latter being provided with a crank arm 31, connected to a connecting rod or link 32, leading downwardly and being connected to a crank 33, of a bell 40 crank member 34, mounted on one of the trunnions 1^a, the second arm of the crank member 34, being connected to a horizontally 45 extending link 35, said link 35, being connected at its front end to a crank 36^a, carried on a rock shaft 36, the latter being operated by means of a foot treadle 37. The foot treadle 37, is keyed or otherwise secured to the rock shaft 36, so as to enable the latter to be rocked or oscillated by the corresponding movement given to the foot 50 treadle 37, and entirely independent of the side members 12, of the foot treadle, such arrangement permitting the trip head 27, to be operated either independently of or in conjunction with the oscillation of the side 55 members 12, of the foot treadle for loosening or tightening the brake drum 10, and clutch and hammer member 7 and 8, connected thereto, and operated as the operator may elect.

60 65 As a means of normally holding the entire foot treadle mechanism in an elevated position and thereby holding the brake strap 10^a, in locked engagement with the brake drum 10, one of the side members 12, is provided with a spiral spring 38, connected to a

bracket 1^b, on a machine base, and as a means of limiting the movement imparted to the slide 28, through the rocking foot treadle 37, as hereinbefore described, and thereby causing the clutch to be released at a predetermined point in the elevation of the hammer head, the bell crank member 34, may be provided with an outwardly extending segment 34^a, provided with adjustable stop pins 34^b, adapted to have limited movements with respect to the adjacent side member 12, of the foot treadle mechanism.

70 75 From the foregoing description, taken in connection with the accompanying drawings, the operation and advantages of my invention will be readily understood.

Having thus described one of the embodiments of my invention, what I claim and desire to secure by Letters Patent, is,—

1. In a drop hammer, a hammer, a shaft, a drum loose on said shaft and connected with said hammer, a brake for said drum, a clutch for connecting said drum with said shaft, and means to variably actuate or release said clutch and to simultaneously release or actuate said brake whereby the length of stroke of the hammer may be varied.

2. In a drop hammer, a hammer, a shaft, a clutch, hammer actuating mechanism rotatably mounted on said shaft and adapted to be engaged by said clutch, a clutch releasing member carried by said mechanism, and a foot controlled trip head adapted to be moved toward and to variable engage said clutch releasing member and disengage said clutch whereby the length of the up-stroke of said hammer may be varied.

3. In a drop hammer, a hammer, a shaft, a clutch, hammer actuating mechanism rotatably mounted on said shaft and adapted to be engaged by said clutch, a clutch operating member, means for variably operating said member and releasing said hammer actuating mechanism for regulating the length of the down-stroke of said hammer, and a foot controlled stepped trip head movable toward and variably engaging said clutch operating member and disengaging said clutch whereby the length of the up-stroke of the hammer may be varied.

4. In a drop hammer, a hammer, a shaft, hammer actuating mechanism rotatable thereon, a clutch for operatively connecting said mechanism to said shaft, a clutch operating member carried by said mechanism, and trip mechanism for variably engaging said clutch operating member to engage and disengage said clutch whereby the length of the down and up-strokes of said hammer may be varied.

5. In a drop hammer, a hammer, a shaft, hammer actuating mechanism rotatable thereon, a brake, a clutch for operatively connecting said mechanism to said shaft, a

- clutch releasing member carried by said mechanism, and foot controlled brake and stepped trip mechanism for controlling said clutch mechanism and variably engaging 5 said brake and clutch releasing member to disengage said clutch whereby the length of the up-stroke of the hammer may be varied.
6. In a drop hammer, a hammer, a shaft, hammer actuating mechanism rotatably 10 mounted thereon, a clutch for operatively connecting said mechanism with said shaft, a clutch operating member carried by said mechanism, a variable trip member on said shaft for engaging said clutch operating 15 member and throwing said clutch into engagement with said hammer actuating mechanism in variable positions whereby the length of the down-stroke of the hammer may be varied, and a foot controlled trip 20 head adapted to engage said clutch operating member in variable positions and disengage said clutch whereby the length of the up-stroke of said hammer may be varied.
7. In a drop hammer, a hammer, a shaft, 25 a hammer actuating mechanism loose on said shaft, a clutch for operatively connecting said mechanism with the shaft, a clutch releasing member carried by said mechanism, and a foot controlled trip head adjustable 30 longitudinally of said shaft, said head having a series of steps whereby by adjustment of said head any one of said steps may be brought into position to engage said member to disengage the clutch whereby the length 35 of the up-stroke of the hammer may be varied.
8. In a drop hammer, a hammer, a shaft, actuating mechanism loose on said shaft and with which the hammer is connected, a 40 clutch for operatively engaging said mechanism with the shaft, and foot controlled clutch engaging and releasing mechanism to variably engage and release said clutch whereby the length of the up and down 45 strokes of the hammer may be varied.
9. In a drop hammer, a hammer, a driving shaft, provided with rotatably mounted clutch and hammer actuating members, means for throwing the latter into and out 50 of engagement with said shaft through said clutch member, and means for operating and means for controlling said means at variable relative positions to said shaft during the rotation of the latter whereby the 55 length of the up and down-strokes of said hammer may be varied.
10. In a drop hammer, a hammer, a driving shaft, provided with rotatably mounted clutch and hammer actuating members, 60 variable trip means for throwing the latter into and out of engagement with said shaft, and means for operating and controlling said variable trip means at variable relative positions to said shaft during the rotation 65 of the latter for changing the terminal

points in the working impulses imparted to said hammer actuating member.

11. In a drop hammer, a frame including guide members, a driving shaft provided with fixed and movable clutch members, a 70 hammer actuating mechanism connected to said movable clutch member, a hammer carried by the hammer actuating mechanism between said guide members, and foot controlled means for actuating and controlling 75 said clutch member at variable positions relative to and during the rotation of said driving shaft whereby the length of the up and down-strokes of said hammer may be varied.

80 12. In a drop hammer, a hammer, a driving shaft provided with rotatably mounted clutch and hammer actuating members, variable means for throwing the latter into engagement with said shaft clutch and, means 85 for throwing the same out of engagement with said shaft clutch and, means for operating and controlling said last mentioned means at variable relative positions to said shaft and hammer actuating member during the rotation of the latter whereby the length of the up and down-strokes of 90 said hammer may be varied.

13. In a drop hammer, a hammer, a frame including guide members, a driving shaft 95 provided with fixed and movable clutch members, a hammer actuating mechanism connected to said movable clutch member and brake drums, a brake strap on the hammer actuating mechanism, a hammer 100 carried by said strap drum between said guide members, and foot controlled means for simultaneously actuating and controlling said clutch and hammer strap and brake drums at variable positions relative to and 105 during the rotation of said driving shaft.

110 14. In a drop hammer, a hammer, a frame including guide members, a driving shaft provided with fixed and movable clutch members, a hammer actuating mechanism connected to said movable clutch member, a hammer carried by the hammer actuating mechanism between said guide members, brake mechanism for said movable clutch and hammer actuating mechanism, and 115 means for simultaneously actuating and controlling said clutch brake and hammer actuating mechanism at variable positions relative to and during the rotation of said driving shaft for regulating the stroke given 120 to said hammer.

115 15. In a drop hammer, a hammer, a shaft, a clutch, hammer actuating mechanism rotatable on said shaft, a clutch operating member carried by said mechanism, variable 125 means for actuating said clutch actuating member to variably engage said clutch with said hammer actuating mechanism whereby the length of the down-stroke of the hammer may be varied, and means for variably en- 130

gaging said clutch actuating member and variably disengaging said clutch and said hammer actuating mechanism whereby the length of the up-stroke of the hammer may be varied.

16. In a drop hammer, a shaft, hammer actuating mechanism rotatable on said shaft, a clutch for connecting and disconnecting said mechanism with said shaft, a clutch actuating and releasing member carried by said mechanism, means for variably actuating said clutch actuating and releasing member and engaging said clutch with said

mechanism whereby the length of the down-stroke of said hammer may be varied, and 15 foot controlled adjustable trip mechanism for engaging said clutch operating member whereby to variably disengage said clutch operating member and thereby varying the length of the up-stroke of said hammer. 20

In testimony whereof I have affixed my signature in the presence of two witnesses.

WILLIAM H. WELCH.
